UNITED STATES PATENT OFFICE.

IRA C. MOORE AND CHARLES FRED TROTT, OF WATERBURY, CONNECTICUT.

DESIGN FOR A GRAVE-MARKER.

SPECIFICATION forming part of **Design No. 26,182**, dated **October 13, 1896**.

Application filed June 20, 1896. Serial No. 596,347. Term of patent 14 years.

To all whom it may concern:

Be it known that we, IRA C. MOORE and CHARLES FRED TROTT, citizens of the United States of America, residing at Waterbury, in 5 the county of New Haven and State of Connecticut, have invented and produced a new and original Design for Grave-Markers, of which the following is a specification, reference being had to the accompanying drawing, 10 showing a front view of the same.

The leading features of our design are the

hand *a*, the scrolled support *b*, the open panel *c*, and the chain-links *d*, raised above and supported from said panel.

What we claim is—

The design for a grave-marker substantially as shown and described. 15
